(57) **CLAIM**

The ornamental design for a carpet, as shown and described.

DESCRIPTION

FIG. 1 is a front, left, top perspective view of a carpet, showing my new design;

FIG. 2 is a rear, right, bottom perspective view thereof;

FIG. 3 is a front elevational view thereof;

FIG. 4 is a rear elevational view thereof;

FIG. 5 is a left side view of the enlarged scale thereof;

FIG. 6 is a right side view of the enlarged scale thereof;

FIG. 7 is a top plan view thereof;

FIG. 8 is a bottom plan view thereof;

FIG. 9 is an enlarged view of detail 9 in FIG. 1;

FIG. 10 is an enlarged view of detail 10 in FIG. 1;

FIG. 11 is an enlarged view of detail 11 in FIG. 2;

FIG. 12 is an enlarged view of detail 12 in FIG. 3;

FIG. 13 is an enlarged view of detail 13 in FIG. 4;

FIG. 14 is an enlarged view of detail 14 in FIG. 7;

FIG. 15 is a front, left, top perspective view of the carpet in a detached state;

FIG. 16 is an enlarged view of detail 16 in FIG. 15;

FIG. 17 is a front, right, top perspective view of the carpet in an alternate configuration;

FIG. 18 is an enlarged view of detail 18 in FIG. 17;

FIG. 19 is an enlarged view of detail 19 in FIG. 17;

FIG. 20 is a front, right, top perspective view of the carpet in an alternate configuration;

FIG. 21 is an enlarged view of detail 21 in FIG. 20; and,

FIG. 22 is an enlarged view of detail 22 in FIG. 20.

The dash-dot-dash broken lines are for notating enlarged views and form no part of the claimed design.

1 Claim, 22 Drawing Sheets
